PAPER TACKING MACHINE

Heinrich Steinberg, Los Angeles, Calif.

Application February 16, 1948, Serial No. 8,711

2 Claims. (Cl. 93—1.1)

1

The present invention relates to a paper tacking machine, wherein the papers that are to be clipped or tacked together are passed between two wheels provided with wedge-shaped teeth or wheels having letters thereon, thus tacking or crimping paper goods or sheets together by high pressure.

The essential feature of the present invention or improvement as hereinafter described lies in the resilient mounting of one of the tacking elements.

The drawings show a front view (Figure 1) and a section through the machine (Figure 2) and a top view (Figure 3) as well as two views of long and half flatsprings (Figures 4 and 5).

This machine is efficient because it has no friction at all and provides the utmost elasticity of the tacking elements. In addition to these two advantages the machine may be adjustable to provide whatever pressure may be desired. I have found by experiments in course of years that the present improvement enables the greatest number of paper sheets to be securely tacked together by increasing the elasticity of one of the tacking elements by employing additional springs as an adjustment. The latter permits a temporary as well as a permanent crimping together.

The tacking or crimping machine essentially consists of a body 1 to be clamped on a table 13 with the clamping screw 3. The bottom tacking or crimping wheel 2a is mounted on a fixed stationary spindle 4a and is rotated by means of a crank handle 11. Both spindles 4a and 4b are parallel.

The mounting of the top fastening element 2b consists of several long flat springs 5 and additional short springs 14 being slotted and flat which bear against the flat faces provided on the spindle 4b of said top element, the said springs being slotted at the middle to clear the top fastening element. Upon these flat long or between these long flat springs are mounted short ones at each side 14. On top of the flat springs are over mounted two springs (spiral springs), in addition to the flat springs 6 at each side or end. The springs are fixed altogether by the screw 7a and the adjustment knob 7b. The adjustment knob regulates the pressure necessary to effect a permanent or a preliminary crimping of paper-stuff together as desired. Figure 4 shows one of the long flat springs, Figure 5 a short one to be mounted between or on top of the flat springs.

To prevent sliding of the spindle 4b while the crank handle is being turned, I have provided in this machine a pin on each side 8 slotted into

2

the both sides of the flat springs. The spiral springs of the spindle in connection with the flat springs increase the elasticity. In order that the invention may be better understood, it will now be described with reference to the accompanying drawings as follows:

Figure 1 shows a front elevational view of the machine. In Figure 1 there are shown flat springs 5, body 1, handle 11, clamping screw 3, fixing screw 7a, adjustment knob 7b, spiral springs 6, upper spindle 4b and upper wheel 2b.

The handle is fixed with the bottom spindle which is bearing the bottom wheel and has to be turned clockwise. The upper wheel is engaged with the bottom wheel under high pressure of the different springs and crimps paper inserted.

Figure 2 shows a section through the machine. The upper element is engaged with the bottom element and a table slotted is provided to carry the paper. A shaped channel 15 guides the paper sheets straight on. The pins 8 on each side fix the flat springs or so called flexible transversal beam in their position during operating and prevent moving or sliding of them.

Figure 3 is a top view of the machine, Figure 4 shows one of the flat springs slotted in their middle for the upper wheel and slotted at each side for the fixing pins, Figure 5 shows half flat springs for use between the long springs or upon them to increase the pressure in connection with the spiral springs.

Having now described my several improvements of the machine and in what manner the same is to be formed I claim the following:

1. A paper tacking machine comprising a body, a spindle on the body and a crimping wheel on the spindle, a second spindle parallel to the first-identified spindle and a second crimping wheel on the second spindle in circumferential engagement with the first-identified crimping wheel, and resilient means for positioning and retaining said second crimping wheel in contact with the first-identified crimping wheel comprising posts on the body on opposite sides of the circumference of said second crimping wheel, a plurality of flat springs having ends loosely engaging the posts and having central apertures therein adapted to receive said second crimping wheel, said second spindle having a position against and beneath the lowermost flat spring, compression spring means between the ends of the flat springs and the posts, adjustable means on at least one of the posts adapted to vary the tension of the compression spring engaging said post, and a

crank on one of the spindles adapted to rotate one of said crimping wheels.

2. A machine as claimed in claim 1, said flat springs being further provided with lateral recesses and said second spindle including upwardly extending projections engaging said lateral recesses.
